(57) **CLAIM**

The ornamental design for a bottle, as shown and described.

DESCRIPTION

FIG. 1 is a top, front perspective view of a first embodiment of a bottle, showing my new design assembled in a first configuration;

FIG. 2 is a front elevation view thereof;

FIG. 3 is a top, front perspective view of the bottle of FIG. 1, shown in a second configuration with the lower bottle portion and cap separated and also detached from the upper section;

FIG. 4 is a front elevation view of the bottle of FIG. 1, shown in a third configuration with the lower bottle portion and cap intact and also detached from the upper section; FIG. 5 is a front elevation view of the bottle of FIG. 1, shown in a fourth configuration and completely exploded for clarity of disclosure;

FIG. 6 is a top, front perspective view of a second embodiment of the bottle, shown in the first configuration;

FIG. 7 is a front elevation view thereof;

FIG. 8 is a top, front perspective view of the bottle of FIG. 6, shown in the second configuration;

FIG. 9 is a front elevation view of the bottle of FIG. 6, shown in the third configuration;

FIG. 10 is a front elevation view of the bottle of FIG. 6, shown in the fourth configuration;

FIG. 11 is a top, front perspective view of a third embodiment of the bottle, shown in the first configuration;

FIG. 12 is a front elevation view thereof;

FIG. 13 is a top, front perspective view of the bottle of FIG. 11, shown in the second configuration;

FIG. 14 is a front elevation view of the bottle of FIG. 11, shown in the third configuration;

FIG. 15 is a front elevation view of the bottle of FIG. 11, shown in the fourth configuration;

FIG. 16 is a top, front perspective view of a fourth embodiment of the bottle, shown in the first configuration;

FIG. 17 is a front elevation view thereof;

(Continued)

FIG. 18 is a top, front perspective view of the bottle of FIG. 16, shown in the second configuration;
 FIG. 19 is a front elevation view of the bottle of FIG. 16, shown in the third configuration;
 FIG. 20 is a front elevation view of the bottle of FIG. 16, shown in the fourth configuration;
 FIG. 21 is a top, front perspective view of a fifth embodiment of the bottle, shown in the first configuration;
 FIG. 22 is a front elevation view thereof;
 FIG. 23 is a top, front perspective view of the bottle of FIG. 21, shown in the second configuration;
 FIG. 24 is a front elevation view of the bottle of FIG. 21, shown in the third configuration;
 FIG. 25 is a front elevation view of the bottle of FIG. 21, shown in the fourth configuration;
 FIG. 26 is a top, front perspective view of a sixth embodiment of the bottle, shown in the first configuration;
 FIG. 27 is a front elevation view thereof;
 FIG. 28 is a top, front perspective view of the bottle of FIG. 26, shown in the second configuration;
 FIG. 29 is a front elevation view of the bottle of FIG. 26, shown in the third configuration; and,
 FIG. 30 is a front elevation view of the bottle of FIG. 26, shown in the fourth configuration.
 The broken lines represent threads between the bottle and caps and form no part of the claimed design.
